UNITED STATES PATENT OFFICE.

ALEXANDER DALLEK, OF NEW YORK, N. Y.

DESIGN FOR A CARD HOLDER.

Application filed October 8, 1926. Serial No. 19,281. Term of patent 3½ years.

To all whom it may concern:

Be it known that I, ALEXANDER DALLEK, a citizen of the United States and a resident of New York city (borough of Bronx), county of the Bronx, and State of New York, have invented a new, original, and ornamental Design for a Card Holder, of which the following is a specification, reference being had to the accompanying drawing, forming part thereof.

Fig. 1 is a top plan view of a card holder showing my new design.

Fig. 2 is a view in end elevation thereof.

I claim:

The ornamental design for a card holder, substantially as shown.

ALEXANDER DALLEK.
